ELECTRO-MECHANICAL SWITCH

Sherman S. Fishman, P.O. Box 321, San Francisco, Calif.

Filed May 24, 1960, Ser. No. 31,311

5 Claims. (Cl. 200—33)

The present invention relates to electro-mechanical switches of the type having multiple particulate metallic circuit closers for controlling the flow of electric current. This device has the advantage of reliable performance at very low temperatures such as operation in a liquid-nitrogen bath. It also has good operating characteristics at temperatures above the boiling point of mercury. This invention is an improvement on my electric switch U.S. Patent 2,935,579, dated May 3, 1960.

The object of my invention is to provide a switch which will operate quietly due to the use of gravity to place the metal particulate circuit closers in the proper position thereby allowing current to flow without being rendered inoperable due to extremely high or low temperature environments.

My invention will be better understood by reference to the following specification and claims. In the accompanying drawings, FIG. 1 is a perspective of the switch and switch housing; FIG. 2 is an elevation partly in section of one embodiment of my switch in the "off" position; FIG. 3 is a schematic elevation of portions of my switch in the "on" position; FIG. 4 is a cross section of my switch taken along lines 4—4 of FIG. 3; FIG. 5 is a cross section of a portion of the switch taken along lines 5—5 of FIG. 4; FIG. 5a is a partial cross section along lines 5a—5a of FIG. 4; FIG. 6 is an elevation of another embodiment of my switch; FIG. 7 is a cross section taken along lines 7—7 of FIG. 6; FIG. 8 is a cross sectional elevation taken along lines 8—8 of FIG. 7 showing the switch in the "off" position; FIG. 9 is a cross sectional elevation of my switch in the "on" position; FIG. 10 is a cross sectional view taken along lines 10—10 of FIG. 9; FIG. 11 is an exploded view of a modified form of the switch; FIG. 12 is a longitudinal cross sectional view of the same modification shown in the "on" position; FIG. 13 is a longitudinal cross sectional view showing another modification in the "on" position; FIG. 14 is a longitudinal cross section of another modified form shown in the "on" position; FIG. 15 is a cross sectional elevation of the switching assembly taken generally along lines 15—15 of FIG. 14 showing the switch mechanism schematically; FIG. 16 is a cross sectional view in the "off" position of a modified form of the switch element; FIG. 17 is an enlarged view of the metal particulate switching elements; FIG. 18 is an enlarged view of another type of metal particulates; FIG. 19 is an enlarged view of yet another type of metal particulates.

Referring in detail to the drawings in which the same reference characters indicate like elements in the different views, FIG. 1 shows a housing assembly comprising a case 15 having contact plates 5a and 5b with a toggle finger 14 projecting through an aperture in the mounting strap 16; FIG. 2 shows the switch assembly of FIG. 3 assembled inside the case 15; FIG. 3 shows the switch assembly comprising a lateral spring support bar 4 with attached contact plate 5b and lateral spring support bar 3 with attached contact plate 5a; the toggle finger 14 has gears which interlock with a plate gear 7 which is fitted on the one side to the non-conductive body 1 and on the other side it is centered by a projection on the lateral spring support bar 4 frictionally fitting into the plate gear depression 7a, an electrode 8b is frictionally attached to the plate gear 7 and passes through the wall of the chamber in the non-conducting body 1 a portion entering said chamber (not shown); FIG. 4 shows the switch assembly

2

in the "on" position with the conducting particles 11 in contact with the electrodes 8a, 8b. Electrode 8a passes through the wall of body 1 and is connected to conductive plate 6a which in turn abuts against the lateral spring support bar 3 which has a projection frictionally fitting into depression 7b. Between electrode 8a and electrode 8b there is a thin barrier 2a which is an arc suppressor. FIG. 5 shows the electrically nonconducting body 1 which has a double-ended hole forming chamber 9 which is covered by enclosing ring 2 thereby preventing the loss of the mass of circuit closers which are conducting particulates 11 and are each uniformly spherical and in the range of 0.5 to 5.0 mm. in diameter. Electrode 8a is shown entering the chamber 9 and making contact with the conducting particulates 11 while electrode 8a' is shown in a position rotated out of the conducting particulates 11' thereby being in the "off" position. FIG. 5a shows the arc suppressor barrier 2a in a cross sectional view. It can be seen in FIGS. 1—5 inclusive that the toggle finger 14 will rotate the switch assembly so that the electrodes 8a and 8b are in the "on" position when in contact with the electrically conducting particulates 11 or in the "off" position when not in contact with the conductive particulates 11'. The switch is assembled with an inert gas or a vacuum in the chamber 9 by means of suitable adhesives or glass-metal seals.

Another modified form of my switch is shown in FIG. 6 where the toggle finger 13 is attached to the retainer ring 12 which is fitted onto the closure ring 2. The lateral spring support bar 4 is in frictional contact with the conductive disc 6b to which is attached electrode 8d. The mounting strap 16a serves as an additional support for the assembly and a guide for the rotary movement of the switch by toggle finger 13. FIG. 7 shows the toggle finger 13 which is held in place by a frictional fit onto the retainer ring 12. The retainer ring 12 is fitted onto the closure ring 2 which fits onto the electrically non-conductive body 1 with the chamber 9 which contains a single electrically conductive ball 10. Electrode 8d projects into the chamber 9, said electrode in the chamber having a socket shaped terminal. The electrode 8d passes through the wall of the chamber 9 and into the disc plate 6b to which it is attached thus securing the disc plate 6b in position against the side wall of body 1. The lateral spring support bar 4 has a projection which fits in the depression in the center of the disc plate 6b thus forming an electrical pathway from the electrode 8d to the lateral spring support bar 4. Likewise lateral spring support bar 3 frictionally engages the disc plate 6a which rests against the body wall 1 and is attached to electrode 8c which has a socket shaped terminal and projects into the chamber 9. FIG. 8 shows this modification of the switch assembly having a single conductive ball 10 in the chamber 9, said ball 10 having its diameter slightly less than the diameter of the chamber 9 into which the socket ended electrode 8c projects. The ring 2 encloses the body 1 so that both open ends of the chamber 9 are covered. Retainer ring 12 is press-fit into a slot in the toggle finger 13. FIG. 9 shows this same embodiment of the switch in the "on" position with the toggle finger 13 rotated so that the metal ball 10 now is at rest in contact with the electrode 8c. FIG. 10 shows the switch in the "on" position for the purpose of tracing the flow of current from the contact plate 5a through lateral spring support bar 3 to disc plate 6a into electrode 8c through conductive ball 10 into electrode 8d through disc plate 6b through lateral spring support bar 4 to contact 5b. Yet another embodiment of my switch is seen in FIG. 11 which has a dished cup 20 having a central depression and rim on its outer aspect and a bevel on its inner aspect, a non-conductive body 23 having a passageway partially

therethrough with one opening forming a chamber 24, a non-conductive ring 23a, multiple metal particulate conductive switching elements 11, a handle ring 19 to which is attached toggle finger 18, and a dished cup 20a which is constructed similarly as is cup 20 and are made of electrically conductive metallic materials such as copper, steel, silver, aluminum. FIG. 12 shows the switch parts assembled with the particulate switching elements resting in contact with the cup 20 and cup 20a, the switch thus being in the "on" position. Ring 23a serves as an insulator between cup 20 and cup 20a. The body 23 is made of refractory electrically non-conductive material and houses the switching elements 11 in the chamber 24. The handle ring 19 is of vitreous electrically non-conductive material and is fusion-welded to cup 20 and cup 20a by a method which will permit chamber 24 to be filled with an inert gas such as argon; or to be evacuated and the switching elements thereby being in a vacuum chamber. FIG. 13 shows the switch parts of the embodiment of FIG. 11 except that the particulate switching elements 11 have been replaced by the single conductive ball 10 which has a diameter slightly less than the diameter of the chamber 24. FIG. 16 is yet another modification of my switch showing the shallow metal cups 60 in juxtaposition forming an enclosure, the refractory body 23 being interposed between the cups which have a socket portion to accept the conductive ball 10, a flat surface to accommodate the insulating ring 23a and a grooved end which permits a glass fusion-weld type seal between the two cups. A further modification of the electrically conductive particulate switching elements 11 are shown in FIG. 17 where a uniformly spherical particulate 70 is seen in the company of a spherical particulate with a single depression 71 and also in company with a spherical particulate with double depressions 72 said particulates in company with each other will tend to cluster in groups closely nested so that the spherical portion of a particulate will fit into the depression portion of another particulate, all particulate elements being in the range of 0.5 to 5.0 mm. in diameter. FIG. 18 shows an additional embodiment of my electrically conductive particulate switching elements where cubes in the range of 0.5 to 5.0 mm. on each side are used. FIG. 19 is yet another modification of my electrically conductive switching elements where prism shaped particulates 74 in the range of 0.5 to 5.0 mm. on a side are used. In place of conductive particulates 11 or ball 10 other varieties of circuit closers such as mixtures of conductive particulates 70, 71, 72 in ratios of 1:10 by weight can be used to obtain different operating characteristics. Similarly, conductive particulates 73 or 74 can be substituted in place of conductive particulates 11 or ball 10. FIG. 14 shows yet another modification of my switch which relies upon the depression of a bar electrode 46 by the contact bar 43 which is an L-shaped form and is attached to the metallic lateral spring support bar 42. The electrode bar 46 is in a housing 44 which is made of electrically conductive material and is embedded in the non-conductive support block 41 having a depression on each side, toggle finger 40 being attached to block 41. The electrode housing 44 abuts against the lateral spring support bar 4. The spring 45 is inside the electrode housing 44 and provides compression for the electrode bar 46 which is held back by retainer blocks 47 which prevent the electrode bar 46 from being ejected from the housing 44 when the switch is in the "off" position. FIG. 15 shows the switch in the "off" position when the toggle finger 50 is moved through arc 49 and the electrode 48 is adjacent to the contact bar 43. When the toggle finger is rotated over path 49 so that the toggle finger 50 is moved to the position of toggle finger 40 then the electrode bar 48 will be rotated to the position of electrode bar 46 which is in contact with the recess in the contact plate 43 and the switch is in the "on" position.

Having described my invention of a new, more effective and less costly electro-mechanical switch, it will be readily appreciated by one skilled in the art that by using various combinations of conductive particulates it is possible to vary the surface area available for carrying current and therefore it is possible to design a switch for low amperage loads or for high amperage loads. Additionally, I have used interchangeable parts in the several modifications which lends itself to greater versatility in manufacture and maintenance by reducing the variety of parts to be used or kept in stock. It can be clearly seen that this new switch has a greater range of operation in extremes of environmental temperatures, has a variable load limit and can be cheaply manufactured.

Modifications of this invention will occur to those skilled in this art and it is to be understood, therefore, that this invention is not limited to the particular embodiments disclosed but that it is intended to cover all modifications which are within the true spirit and scope of this invention.

What I claim as new and desire to secure by Letters Patent of the United States is:

1. An electro-mechanical switch assembly comprised of a non-conductive cylindrical body, said body having an open passageway extending through the body forming a chamber which is approximately perpendicular to the axis of the cylinder; a quantity of conductive particulate circuit closers, said particulates being disposed in said chamber; a conductive metallic circular disc plate having a depression at its center, said disc plate being fitted onto one flat end surface of said cylindrical body; a conductive metallic circular plate having on its side a gear with a central depression, said gear plate being fitted onto the other flat end surface of said cylindrical body; a non-conductive tubular closure ring, said ring being fitted about the aforesaid assembled parts; a pair of conductive metallic electrodes, one electrode passing through said plate gear and said cylindrical body, said electrode projecting partly into said chamber, the other end of said electrode being frictionally attached to said plate gear; the second electrode passing through said disc plate and said cylindrical body, said electrode projecting partly into said chamber, the other end of said electrode being frictionally attached to said disc plate, said pair of electrodes being so disposed that said electrodes are opposed but not in contact thereby forming a space between them; a non-conductive arc suppressor barrier, said barrier passing through said closure ring and projecting partially into said chamber and being disposed in the space between said opposed electrodes; a pair of metallic lateral spring support bars each having a central projection; a non-conductive housing case having an aperture therein; said support bars being fitted into said case aperture and in opposition to each other but not in contact; the aforesaid assembled parts being fitted into said aperture and having the depression of said disc plate in frictional contact with the projection of said support bar on one side and the depression on said plate gear in frictional contact with the projection on said support bar on the other side; said depressions and projections forming a joint thereby providing a stationary axis of rotation about which said switch assembly is adapted to be rotated while being mounted in said case to prohibit axial movement thereof; a non-conductive toggle finger having a gear configuration at one end and a handle at the other end, said gear configuration being meshed with said gear plate; a mounting strap having a central aperture, said mounting strap being fitted onto said case so that said toggle finger handle projects through the aperture of said mounting strap.
2. An electro-mechanical switch assembly comprised of a non-conductive cylindrical body, said body having an open passageway extending through the body forming a chamber which is approximately perpendicular to the axis of the cylinder; a metallic conductive circuit closer ball having a diameter slightly less than the diameter of said

chamber, said ball being disposed inside said chamber; a pair of conductive metallic circular disc plates having a central depression, said disc plate being fitted onto a flat end surface of said body, the other said disc plate being fitted onto the opposing flat end surface of said body; a pair of electrodes having a flat surface at one end and a socket shaped terminal at the other end, an electrode passing through said disc plate, said circular body, and having its socket shaped terminal projecting into said chamber, the flat end being frictionally attached to said disc plate; the other electrode passing through said opposed disc plate, said body wall and having its socket shaped terminal projecting into said chamber being opposed but not in contact with the first electrode projecting therein, the flat end of said second electrode being frictionally attached to said opposed disc plate; a non-conductive tubular closure ring, said closure ring being fitted about the aforesaid assembled parts; a non-conductive retainer ring having a centrally located flange, said retainer ring being fitted about the aforesaid assembled parts; a pair of metallic lateral spring support bars each having a central projection; a non-conductive housing case having an aperture therein, said support bars being fitted into said case aperture and in opposition to each other but not in contact, the aforesaid assembled parts are fitted into said aperture having the depression of said disc plate in frictional contact with the projection of said support bar on one side and the depression on said disc plate in frictional contact with the projection on said support bar on the other side; said depressions and projections forming a joint thereby providing a stationary axis of rotation about which said switch assembly is adapted to be rotated while being mounted in said case to prohibit axial movement thereof; a non-conductive toggle finger having a handle at one end and a recess at the other end, said recess being frictionally engaged with the flange of said retainer ring; a mounting strap having a central aperture, said mounting strap being fitted onto said case so that said toggle finger handle projects through the aperture of said mounting strap.

3. An electro-mechanical switch assembly comprised of a pair of metallic conductive dished cups having a central depression and a rim on their outer aspect and a bevel on their inner aspect; a non-conductive cylindrical body said body having an open passageway extending partially through the body forming a chamber which is approximately perpendicular to the axis of the cylinder, said body being fitted into the dished portion of the first of said cups, a quantity of conductive particulate circuit closers, said particulates being disposed in said chamber; an insulation ring, said ring being fitted about said body; a vitreous fusion ring, said fusion ring being fitted about the aforesaid cup and so disposed that the outer rim of said cup abuts against the edge of said fusion ring; a second said cup being fitted onto said body so that its inner edge is in contact with said insulation ring and the outer rim of said cup abuts against the other edge of said fusion ring; a non-conductive toggle finger, said toggle finger being attached to said fusion ring; a pair of metallic lateral spring support bars each having a central projection; a non-conductive housing case having an aperture therein, said support bars being fitted into said case aperture and in opposition to each other but not in contact; the aforesaid assembled parts are fitted into said aperture having the depression of said cup in frictional contact with the projection of said support bar on one side and the depression on the second cup in frictional contact with the projection on the opposite said support bar; said depressions and projections forming a joint thereby providing a stationary axis of rotation about which said switch assembly is adapted to be rotated while being mounted in said case to prohibit axial movement thereof; a mounting strap having a central aperture, said mounting strap being fitted onto said case so that said toggle finger projects through the aperture of said mounting strap.

4. An electro-mechanical switch assembly comprised

of a pair of metallic conductive dished cups having a central depression on their outer aspect and on their edge a socket portion, a flat portion and a grooved portion; a non-conductive cylindrical body said body having an open passageway extending partially through the body forming a chamber which is approximately perpendicular to the axis of the cylinder, said body being fitted into the dished portion of the first of said cups; a circuit closer being comprised of a single electrically conductive metallic ball having a diameter slightly less than the diameter of said chamber, said ball being disposed in said chamber; an insulation ring, said ring being fitted about said body and so disposed as to be in contact with the flat portion of the first said cup; the second said cup being fitted onto said body so that the first and second cups are opposed, the flat portion of said second cup abutting against the exposed surface of said insulation ring; a quantity of vitreous fusion substance, said vitreous material completely filling the grooves of said opposed pair of cups; a pair of metallic lateral spring support bars each having a central projection; a non-conductive housing case having an aperture therein, said support bars being fitted into said case aperture and in opposition to each other but not in contact, the aforesaid assembled parts are fitted into said aperture having the depression of the first said cup in frictional contact with the projection of said support bar on one side and the depression on the second said cup in frictional contact with the projection on said support bar on the opposite side; said depressions and projections forming a joint thereby providing a stationary axis of rotation about which said switch assembly is adapted to be rotated while being mounted in said case to prohibit axial movement thereof; a non-conductive toggle finger having a handle at one end and a recess at the other end, said recess being frictionally engaged with the grooved portions of said pair of cups; a mounting strap having a central aperture, said mounting strap being fitted onto said case so that said toggle finger handle projects through the aperture of said mounting strap.

5. An electro-mechanical switch assembly comprised of an electrode bar having a thicker central portion, a round end and a flat end; a metallic spring, said spring being fitted onto the flat end of said electrode; a single opening metallic electrode housing, said flat end electrode with spring being disposed inside said housing, said electrode having its thickened central portion in sliding contact with the walls of said housing, the rounded end of said electrode projecting partially from the opening of said housing; a pair of retaining brackets, said brackets fitted onto the opening of said housing; a non-conductive support block having an off-center open passageway partially therethrough, a central opening communicating with said passageway and a central depression on the side opposite said central opening, said housing being fitted into said passageway; a metallic lateral spring support bar with a centrally located projection, a second metallic lateral spring support bar with centrally located projection having another central attachment to an L-shaped metallic form having a contact recess at its end, a non-conductive housing case having an aperture therein, said support bars being fitted into said case aperture and in opposition to each other but not in contact, the aforesaid assembled parts are fitted into said case aperture having the depression of the metallic lateral spring support bar fitted into the central opening thereby being in contact with the wall of said metallic housing; the projection of the support bar with L-shaped form is in frictional contact with the central depression of said block, said depression and projection and opening and projection forming joints thereby providing a stationary axis of rotation about which said switch assembly is adapted to be rotated while being mounted in said case to prohibit axial movement thereof; a non-conductive toggle finger, said toggle finger being attached to said block;

a mounting strap having a central aperture, said mounting strap being fitted onto said case so that said toggle finger projects through the aperture of said mounting strap.
